TOOTHBRUSH

Elbert Armstrong McManis and Walter Scott
Uhler, Baltimore, Md.

Application April 18, 1938, Serial No. 202,770

2 Claims. (Cl. 15—135)

This invention refers to toothbrushes and more particularly to those of the portable pocket type, with parts arranged for renewal or adjustment.

The main object of this invention is to provide a tubular handle designed to serve as a sanitary protector for the brush bristles and to contain a dentifrice tube so connected as to supply the brush in a convenient and suitable manner. Another object is to provide an adjustment 5 that will control the flow of dentifrice to the brush. Other objects will become apparent as the invention is more fully set forth.

In this invention, a hollow toothbrush head is used, with a passage running internally to and 15 through the shank of the brush. The shank is attached to a hollow barrel that holds a conventional dentifrice tube securely with its mouth pointing towards the passage so as to conduct the dentifrice through the brush to the bristles. 20 At the same time pressure may be brought on the tube by a closure member acting on the barrel without necessitating contact with the user to pinch the tube with his hands. The toothbrush is arranged in a tubular casing that 25 protects the parts of the same and provides a very convenient form for carrying around in the pocket.

In the drawing which illustrates an embodiment of this invention:

30 Figure 1 is a general view of a toothbrush embodying this invention.

Figure 2 is a longitudinal section through the toothbrush with parts separated to indicate their manner of attachment.

35 Figure 3 is a transverse section through the toothbrush on the line 3—3 of Figure 2.

Similar reference characters refer to similar parts throughout the drawing.

In the drawing, 1 represents a hollow cap 40 adapted to fit closely over the exterior surface of a cylindrical barrel 2 to a rib 3. A cylindrical pencil shell 4 also fits on the barrel and against the rib 3, being arranged to meet the cap 1 without any open seam between them, as 45 indicated in Figure 1.

The barrel 2 is preferably constructed as shown 50 in the sectional view, its front end portion 5 being bevelled towards a neck piece 6. Its rear end portion 7 is reduced in diameter and screw threaded to receive the internal screw threads 8 of a cylindrical thimble 9. An enlarged chamber 10 is provided within the barrel to receive 55 a dentifrice tube 11. The latter is placed in the chamber 10, and its threaded neck 12 screwed into an internal screw threaded portion 13 in the

neck piece 6. Threading the tube thus in place secures the former substantially and prevents leakage when the dentifrice 20 is squeezed out. A passage 14 in the barrel 2 serves to conduct the dentifrice through it and into a passage 15 5 in the toothbrush head 16. It passes out of the head 16 through an orifice 17 to and among the bristles 18 of the toothbrush. The toothbrush head 16 proper is bent from its connecting shank at an angle to dispose it offset from the screw 10 threaded end portion of same that screw-threads into the neck piece 6. The off-setting of this brush head affords room for the head when placed in the cap 1, to come adjacent to the wall thereof, and for ample space in front of the 15 bristles. This prevents the bristles from becoming stuck to the wall, even when toothpaste dries thereon, as frequently happens with toothbrushes not so spaced. This arrangement also gives leverage for screwing the shank into the 20 neck 6. The bend in the shank has the function of resisting the flow of dentifrice through its passage 14 to the extent of preventing spurts of this material out of it, yet a gradual exuding. This form also enables the toothbrush to be 25 more effectively and conveniently used on the back of the teeth as it can be manipulated with ease for this purpose. Its offset construction enables the toothbrush head to be handled with 30 more convenience when same is cleaned exteriorly and interiorly and has other advantages. The neck 12 for receiving the end portion of the dentifrice tube, projects into the barrel 2, as indicated, to allow the bevelled spout of the tube 11, to compress against it and turn partly 35 inside-out thereon. This allows the dentifrice to be more completely expelled from the tube, and thereby prevents the waste that would otherwise occur.

The chamber 10 is made large enough to permit the tube 11 to go in easily and permit its being squeezed longitudinally. The thimble 9 has a plunger 19 that squeezes against the tube as the barrel cap is screwed on the end portion 7. This barrel cap has a spool 21 for floss 22 as 40 shown and a suitable holder 23 for a lipstick 24. This lipstick extends toward the pencil portion 25 in which a pencil 26, and adjuster 27 is connected for propelling the pencil for use. 45

The pencil shell is preferably made as indicated in the drawing.

In the use of the device (assuming the toothbrush is closed as shown in Figure 1, and ready for service) the caps 1 and 4 are removed. The thimble 9 is screwed on until its plunger 19 55

presses on the tube 11 and forces sufficient dentifrice out onto the bristles. The toothbrush is then utilized in the usual manner.

The floss is taken off as needed and the lipstick is used as required. The pencil is operated in the conventional manner. After use, the cap 1 and the pencil shell 4 are mounted on the barrel 2 and the device replaced in the user's pocket, purse or bag, where it will be out of the way, and its internal parts safely protected.

While but one form of the invention is shown in the drawing, it is not desired to limit this application for patent to this particular construction, otherwise than limited by the prior art, as it is appreciated that other forms might be made that would use the same principles and come within the scope of the appended claims. Having thus described the invention, what is claimed is:

20 1. In a toothbrush structure, the combination of a hollow toothbrush head arranged for the extrusion of dentifrice therethrough, a barrel arranged for holding the brush head with a dentifrice passage in registry with the hollow portion of the head, said barrel having a boss extending into the interior of the barrel and adapted to hold the neck of a dentifrice tube in registry with the said passage for extrusion of its contents therethrough to the brush, said connecting portions of the barrel with the brush and the tube having an intervening passage for providing for the predetermined flow of the dentifrice stream, a thimble fitting on the barrel having a cylindrical plunger insertable and operable in the barrel and slightly smaller in cross-

section than that of a dentifrice tube placed therein and spaced away from the walls of the barrel to permit the tube to spread out conveniently when collapsed by the pressure of the plunger thereon and to upset the tube on the 5 boss when the collapsing portions approach said boss.

2. In a toothbrush structure of the class described, the combination of a removable toothbrush head with an offset shank having a dentifrice passage therethrough to the bristles of the brush, a hollow barrel having a conical head portion arranged with an enlarged orifice projecting exteriorly for receiving and holding the said shank and with an interiorly projecting boss 15 with an enlarged orifice for receiving and holding the neck of dentifrice tube and with a narrow intervening passage in between the said enlarged orifices for providing a predetermined forming of the dentifrice therethrough, the interior of the barrel adjacent to the boss being converged around about same and spaced therefrom and adapted to provide an upsetting space for the tube to collapse in near the end of its collapsing, a thimble adjustably mounted on the 20 exterior of the barrel having an internal plunger therein of cylindrical form and adapted to contact the rear of a dentifrice tube placed in the barrel and spaced from the walls thereof to permit the tube to be collapsed and widened therein, and means on the barrel for definitely limiting the travel of the thimble on the barrel.
